(57) **CLAIM**

The ornamental design for a flashlight, as shown and described.

DESCRIPTION

FIG. 1 is a top plan view of a flashlight according to the present invention.

FIG. 2 is a front elevational view of the flashlight.

FIG. 3 is a left side elevational view of the flashlight, with the right side elevational view being the mirror image of the left side elevational view.

FIG. 4 is a rear elevational view of the flashlight; and, FIG. 5 is a bottom plan view of the flashlight.

The portions shown in broken lines are for illustrative purposes only and form no part of the claimed design.
